His Attorney.

UNITED STATES PATENT OFFICE

WALTER ADAM, OF BERLIN-OBERSCHENNEWAIDE, GERMANY, ASSIGNOR TO GENERAL ELECTRIC COMPANY, A CORPORATION OF NEW YORK

ELECTRICAL SWITCH GEAR

Application filed October 11, 1930, Serial No. 488,146, and in Germany November 27, 1929.

My invention relates to electrical switch-gear, and more particularly to means for isolating and covering the stationary disconnecting contacts of the truck or draw-out type of electrical switchgear.

During the operation of disconnecting the movable draw-out switch unit with respect to the live stationary bus and feeder contacts, the movement, whether horizontal or vertical, of the switch unit or truck is generally accompanied by a further isolating operation wherein the stationary contacts connected to the live bus bars and other electrical connections are covered and enclosed by a shield or shutter-like arrangement so that the operator is protected from coming into contact with live parts when the switch unit is withdrawn from its operative connected position. It is also important that the stationary contacts be effectively protected from dust or atmospheric influences when in the isolated position so that the contacting surfaces thereof shall not be corroded or coated with material increasing the contact resistance. In apparatus of the character above described it is the usual practice to arrange the isolating shutter apparatus with respect to the movable switch unit so that the shutters are automatically opened and closed by the switch unit when it is moved to its operative or connected, and inoperative or disconnected positions respectively.

For example, an arrangement which has been used comprises a shutter or cover having a curved surface representing a portion of a cylindrical member. The axis of rotation of the shutter is likewise the axis of the cylindrical member and is arranged at right angles or vertical to the axis of the casing or housing within which the stationary isolating contacts are mounted. When the cross section of this housing is of circular or elliptical cross section, as is often the case, the seating surface for the shutter corresponds to a mathematically complicated curve which involves obvious difficulties in design and construction. A further disadvantage of this arrangement resides in the fact that the shutter when closed does not necessarily seat tightly on the

housing since pressure is not exerted to force the shutter firmly on to its seat.

My invention has for its principal object the provision of an improved shutter arrangement for stationary isolating contacts which shall have means for biasing the shutter directly against its seat in the closed position thereof and for moving the shutter directly away from its seat prior to its uncovering movement during the opening operation thereof.

In accordance with my invention the housing for the stationary isolating contacts may be constructed with the usual cylindrical or elliptical cross section and the shutter may comprise a simple plate-like member adapted to cover and fit tightly over the open end of the housing when in the isolating position. For the purpose of operating the shutter, there is employed a lever system related to the movable switch unit in such a manner that during the opening movement of the shutter it is at first moved approximately in a straight line substantially perpendicular to the seating surface and is then moved in a lateral or sidewise direction so as completely to uncover the stationary isolating contact.

My invention will be more fully set forth in the following description referring to the accompanying drawing and the features of novelty which characterize my invention will be pointed out with particularity in the claims annexed to and forming a part of this specification.

Referring to the drawing, Fig. 1 is a fragmentary elevational view of truck-type switchgear embodying my invention; Fig. 2 is a fragmentary view of apparatus illustrated in Fig. 1 showing the shutter in an intermediate position, and Fig. 3 is a similar view showing the shutter in the open position thereof.

In Fig. 1 there is illustrated truck-type switchgear comprising a stationary structure 1 and a movable unit 2 operable between connected and disconnected positions with respect to the stationary structure 1. The stationary structure in the present instance comprises a plurality of housings or casings 3 for the live busses and feeders (not shown) 100

which are insulated in any suitable manner with respect to the enclosing housings. The stationary disconnecting or isolating contacts (not shown) are electrically connected in any suitable manner to the busses and are individually mounted within housings 4, 5 and 6 of suitable cross section, as cylindrical or the like, which are open at their outer ends and adapted to be closed by the cover or shutter members 7, 8 and 9 respectively. In the housings 4 and 5 are disposed the stationary isolating contacts connected to the busbars whereas the isolating contact for the outgoing line or feeder is arranged in the housing 6.

15 The movable draw-out truck unit 2, on which is mounted a switch (not shown), as an oil circuit breaker, comprises the movable isolating or disconnecting contacts 10, 11 and 12 for coacting with the stationary isolating contacts arranged within the housings 4, 5 and 6 respectively. The movable contacts are mounted on and move as a unit with the truck which is usually mounted upon wheels so that it may be rolled into operative or inoperative position.

20 For the purpose of operating the shutter members 7, 8 and 9 so that they will automatically open to uncover the isolating contacts when the movable truck unit 2 is moved into operative position, and vice versa, there is provided a lever system for each shutter comprising a bellcrank 13 pivotally mounted on the corresponding housing and pivotally connected at one end 25 at 13' to a lever 14 having a sliding connection, by reason of the slot 15, with a fixed pin 16 also mounted on the housing. At the outer end of the lever 14 is mounted the corresponding shutter comprising a plate-like member biased firmly when in the closed position as illustrated in Fig. 1 against the outer edge of the contact enclosing housing by the spring 17 which is connected at one 30 end to the housing and at its other end to the lever 14. One of the bellcranks 13 is connected with an operating member or 35 crank 18 for coaction with an actuating member or lug 19 mounted and carried by the movable truck unit 2, the bellcranks 13 being interconnected by the links 20 and 21 for insuring simultaneous operation thereof.

40 Assuming that the switchgear is in the position illustrated in Fig. 1 and that the movable unit 2 is to be moved into operative position wherein the movable contacts 10, 11 and 12 are in engagement with their coacting contacts, movement of the switch unit towards operative position causes the actuating member or lug 19 to engage the operating member 18 at the recess 18' so that continued movement of the truck unit causes simultaneous rotation through the interconnecting lever mechanism of the bellcranks 13. Since the initial rotative movement of the pivotal connection 13' of each

bellcrank with its lever 14 is approximately in a linear or horizontal direction, the corresponding shutter is at first moved directly outwardly and away from its seat against the bias of spring 17. As the rotative movement of the bellcrank 13 is continued, referring to a single shutter mechanism, the link 14 continues to move outwardly by reason of the slot 15 and starts to pivot about the pin 16 as illustrated in Fig. 2. In this position, the shutter has moved a sufficient distance away from its seat so that it may be moved laterally in a pivotal manner without obstruction. When the shutter has moved to a position so that the toggle formed by the lever 14 and the bellcrank 13 has passed the dead center position, the spring 17 acts to pull the shutter to the position illustrated in Fig. 3 and to retain it in such position until it is positively actuated by the movable truck unit towards the covering or isolating position. In the position illustrated in Fig. 3, the shutter is disposed along the outer side of the corresponding housing so that it is entirely out of the way and occupies but little space when the switch unit is in operative position.

45 When the truck unit 2 is withdrawn to its isolating position, the reverse operation is performed, the member 19 serving to cam the operating member 18 in a counterclockwise direction and to insure simultaneous operation of the shutters to the closed position illustrated in Fig. 1 wherein the shutters are each firmly biased by the spring 17 towards their seating surfaces so that dust or gases in the surrounding air are effectively precluded from coming into contact with the stationary contacts. As in the uncovering operation, the springs 17 act to complete the operation after the toggle above described has passed dead center. Accordingly, the actuating lug 19 need only effect part of the covering and uncovering operations since the springs are effective to complete the final part of the operations. If desired, the springs 17 may be replaced by a single spring of sufficient strength coacting with the interconnecting lever mechanism for operating the bellcranks as a unit.

50 It shall be understood that my invention is not limited to the specific truck type switchgear herein illustrated but is equally applicable to other draw-out or drop-down types wherein a movable switch unit is provided with isolating contacts for coaction with the stationary contact structure.

55 It should be understood that my invention is not limited to specific details of construction and arrangement thereof herein illustrated, and that changes and modifications may occur to one skilled in the art without departing from the spirit of my invention.

60 What I claim as new and desire to secure by Letters Patent of the United States is:

1. In electrical switchgear including a stationary bus structure having isolating contacts for coacting with contacts carried by a switch unit movable with respect to said stationary structure and an enclosing housing open at one end for said isolating contacts, means for covering and uncovering said stationary isolating contacts in accordance with the position of said movable unit comprising
- 10 a cover member coacting with the open end of said housing, means for biasing said cover member directly against its seating surface with said housing when it is in the isolating position, and means coacting with said movable unit for moving said cover member longitudinally away from its seat and then laterally to the uncovering position.
2. In electrical switchgear including stationary bus structure having disconnecting contacts for coacting with contacts carried by a switch unit movable with respect to said bus structure, isolating means for covering each of said stationary disconnecting contacts when said switch unit is in the isolated
- 20 disconnecting position thereof comprising a cover member operable to a position for isolating said stationary disconnecting contact, means coacting with said movable unit for imparting pivotal movement to said member during part of the isolating operation, and means for biasing said cover member in a linear direction in its isolating position.
- 25 3. In electrical switchgear including a stationary bus structure having disconnecting contacts for coacting with movable disconnecting contacts carried by a switch unit movable with respect to said stationary structure and an enclosing housing for each stationary disconnecting contact open at one end for receiving the coacting movable disconnecting contact, means for covering and isolating each of said stationary disconnecting contacts when said switch unit is in the
- 30 inoperative disconnecting position comprising a cover member adapted to seat at the open end of said housing, a lever having a sliding connection for moving said cover member pivotally and then longitudinally
- 35 into seating position, and means connected to said lever coacting with said movable unit for causing closing of said cover member to isolating position when the switch unit is withdrawn and for moving said member to uncovered position when said unit is moved into operative position.

- 40 4. Isolating structure for stationary disconnecting contacts coacting with movable disconnecting contacts carried by a movable switch unit comprising an enclosing housing for each of said stationary contacts, said housing being open at one end for receiving the coacting movable contact, and a plate-like cover member pivotally and reciprocally mounted with respect to said housing where-

by said cover member may be pivotally moved from a lateral position and thereupon longitudinally moved against its seating surface at the open end of said housing to effect isolation of said contact, and a lever mechanism coacting with said movable unit for causing opening and closing of said cover member in accordance with the position of said unit.

45 5. Isolating structure for stationary disconnecting contacts coacting with a movable switch unit, comprising a contact enclosing housing, a plate-like member for covering one end of said housing in the contact isolating position, a lever connected to said member adapted for pivotal and longitudinal movement, means connected to said lever coacting with said movable unit for causing longitudinal movement of said member away from its seating surface during the

50 initial opening movement thereof and for thereafter imparting pivotal movement to said member for moving the same laterally to open position.

55 6. Isolating structure for the stationary disconnecting contacts of truck-type switchgear including a movable switch unit, comprising a cover member adapted to be moved to an isolating position, a lever connected to said cover member for moving the same into and out of the isolating position, said lever being provided with a pin and slot connection for permitting pivotal and reciprocal movements thereof, resilient means acting on said lever to bias said cover member into firm seating position in the isolating position thereof, and means including a crank connected to said lever coacting with said movable unit for imparting longitudinal movement to said cover member with respect to its seat against the bias of said resilient means and for also imparting an uncovering pivotal movement thereto in response to movement of said unit to operative position.

60 7. Isolating structure for the stationary disconnecting contacts of truck-type switchgear including a movable switch unit, comprising an enclosing housing open at one end for each of the stationary contacts, a cover member pivotally and reciprocally mounted movable laterally over the open end of each of said housings, linkages interconnecting said cover members for insuring simultaneous operation thereof, spring means for biasing said cover members in a longitudinal direction against the seating surfaces thereof in the isolating position and for likewise maintaining the cover members in open position, and a crank operatively connected to said linkages coacting with said movable unit for causing simultaneous operation of said cover members in accordance with the position of said movable unit, each of said cover members being actuated in a longitudi-

nal direction with respect to its seat when moving into and from isolating position.

8. In electrical switchgear including stationary disconnecting contacts and a movable switch unit cooperating therewith, isolating structure for each of said stationary disconnecting contacts comprising an enclosing housing open at one end, a plate-like cover adapted to seat on the open end of said housing in the isolating position, a lever mounted on said housing for pivotal and longitudinal movements, said lever operatively connected to said cover, a crank connected to said lever forming a toggle therewith, a spring operatively connected to said toggle for biasing said cover into either the open or isolating position thereof, and an actuating member carried by said movable switch unit coacting with said crank for causing operation of said cover in accordance with the position of said unit.

In witness whereof, I have hereunto set my hand this 29th day of September, 1930.

WALTER ADAM.
